UNITED STATES PATENT OFFICE.

ROBERT CARL OLSON, OF ZION, ILLINOIS.

FEED DISTRIBUTOR.

Application filed October 29, 1924. Serial No. 746,645.

To all whom it may concern:

Be it known that I, ROBERT C. OLSON, a citizen of the United States, residing at Zion, in the county of Lake and State of Illinois, have invented a new and useful Feed Distributor, of which the following is a specification.

This invention relates to a device designed primarily for distributing feed to poultry, one of the objects of the invention being to provide a structure of this character which, at a predetermined time, will be released so as to operate automatically to broadcast feed so that it will be scattered in the vicinity of the structure.

A further object is to provide a device of this character which, when released, will operate by gravity not only to free the feed but also to broadcast it.

Another object is to provide a means for imparting an initial impulse to the movable portion of the structure when released.

A still further object is to provide novel means for closing the container portion of the device, said closure being adapted to open automatically as the structure begins to operate.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings—

Figure 1 is an elevation of the feed distributor, a portion of the time controlled release mechanism being broken away and the broadcasting container being illustrated by full lines in normal or set position and by broken lines in one of the positions assumed thereby during the broadcasting operation.

Fig. 2 is a top plan view of the structure.

Fig. 3 is an elevation of the time controlled release mechanism.

Fig. 4 is a bottom plan view of a portion of the disk.

Fig. 5 is a plan view of a portion of the bottom disk showing a ratchet structure.

Figure 6 is a section on line 6—6 Figure 55 showing the spiral in elevation.

Referring to the figures by characters of reference 1 designates a suitable supporting structure to which is secured the upper end 2 of a depending twisted guide strip or spiral 3, the lower end of which has an enlargement or stop 4. That portion of this spiral guide nearest the collar 4 is reduced to form a round stem 5.

Slidably mounted on the spiral 3 is a container 6 having legs 7 at desired intervals which connect the open bottom of the container to a frusto-conical distributing or broadcasting disk 8. This disk projects radially beyond the wall of the container 1 and this projecting portion is slit radially as shown at 9 to provide separate blades 10. An elongated opening 11 is formed in the disk 8 and is adapted to fit loosely on a spiral 3 so that, as the disk 8 and container 6 descend by gravity, a rotary motion will be imparted thereto in the direction indicated by the arrow in Fig. 2. The advancing edges of the blades 10 are free of projecting portions but the opposed or following edges of the blades are provided with upturned flanges 11. Thus it will be apparent that as the container and disk rotate the material distributed from the disk by centrifugal force and by gravity will be thrust outwardly by the flanges 11.

The opening between disk 8 and the wall of container 6 is normally closed by a band 12 loosely mounted on the container and having inclined slots 13. Studs 14 project from the container and into these slots and when the container is in its normal or closed position, the studs are located in the upper portions of the slots. A stud 15 projects from band 12 and is adapted to engage a hanger 16 depending from the structure.

A lug 17 projects from the top of the container 6 and normally bears against a finger 18 projecting from one end of a lever 19. The other end of this lever extends close to a cam 20 carried by the winding stem 21 of the alarm mechanism of a clock. This clock is suitably supported on the structure 1 and can be set so that the alarm mechanism will be released at any predetermined time.

Another lug 23 is extended from the top of the container 6 and is engaged by a hook 24 which, in turn, is connected by a spring

25 to the structure 1. This hook merely bears against the lug 23, it being held in engagement therewith by the tension of spring 25.

25. In using the device, the container 6 is 5 filled with the grain or other food to be scattered and is brought to its raised position with the lug 17 in engagement with the finger 18. Hook 24 is then placed in engagement with lug 23 so as to hold spring 25 10 under tension. When the container is thus located upon the upper portion of the spiral 3, the stud 15 will be supported back of the lower portion of hanger 16 and the closure band 12 will rest upon the disk 8, thereby 15 preventing escape of the contents of the container.

When, at a predetermined time, the alarm mechanism of the clock is actuated, cam 20, which rotates with stem 21, will thrust 20 against lever 19 and shift its finger 18 out of the path of lug 17. Thus spring 25 will be allowed to contract and will thereby impart an initial rotary impulse to the container 6. As the container rotates, it also 25 descends along the spiral 3 but during the first portion of this movement, the stud 15 is held against rotation by hanger 16. Thus as the container rotates within the held band 12, the disk 8 will move downwardly away 30 from the band and will allow grain to escape under the band. The grain will be thrown outwardly by centrifugal force and the blades 10 and flanges 11 will operate to scatter the grain considerable distances. 35 This operation continues until the container reaches its lowermost position at which time disk 8 rests upon the collar 4 and is allowed to spin with the container 6 upon the stem 5 until its momentum is lost.

40. This structure can be readily installed and is advantageous because it insures proper broadcasting of the feed at any predetermined time.

45. If desired, and as shown in Fig. 5, the bottom of the container can be provided with an opening 25 covered by a ratchet disk 26 which is connected to but adapted to rotate upon the bottom 27 of the container as shown in Figure 6. A spring pressed pawl 50 28 is pivotally mounted on the bottom 27 and normally engages the teeth of the ratchet disk 26. A slot 29 is provided in the ratchet disk 26 and is adapted to slidably engage the spiral 30.

55. It will be apparent that when the container is moved upwardly along the spiral the ratchet disk 26 will be free to rotate relative to the bottom 27 because the teeth of the ratchet disk can, during this movement, slip 60 past the end of the pawl 28. When the container moves downwardly, however, the rotating disk 26 will thrust against the pawl 27 and cause the container to revolve. With this arrangement the container can be more 65 quickly raised than where it is necessary to

revolve it during the upward movement as in the structure shown in Fig. 1.

What is claimed is:

1. The combination with a spiral guide stem and a support therefor, of a container mounted to slide and rotate upon the stem, a broadcasting disk spaced from but rotatable with the bottom portion of the container, means for holding the container against rotation, time controlled means for releasing the container, means for imparting an initial impulse to the container when released, a closure for the container, and means for opening the closure during the actuation of the container. 80

2. The combination with a spiral guide strip and a support therefor, of a container mounted to gravitate and rotate upon the stem, a broadcasting disk spaced from but rotatable with the lower portion of the container, radial blades at the margins of the disk, upwardly projecting flanges upon the blades, means for holding the container against rotation, means for releasing the container, a closure for the container, and means for shifting the closure during the actuation of the container, thereby to release the contents of the container. 85

3. The combination with a spiral guide stem and a support therefor, of a container mounted to gravitate and rotate upon the stem, a broadcasting disk spaced from but rotatable with the bottom portion of the container, means for releasing the container, means for imparting an initial impulse to the rotation of the container when released, a closure for the container, and means for retarding the movement during the actuation of the container, thereby to release the contents of the container. 90

4. The combination with a spiral guide stem and a support therefor, of a container mounted to gravitate and rotate upon the stem, a broadcasting disk spaced from but rotatable with the container, a band movably mounted on the container and normally supported by the disk to retain the contents of the container, means for holding the container against rotation, means for releasing the container, means for holding the band against rotation during the initial portion of the rotation of the container, and cooperating means upon the band and container for changing the relative positions of the disk and band to release the contents of the container. 100

5. The combination with a spiral guide stem and a support therefor, of a container mounted to gravitate and rotate upon the stem, a broadcasting disk spaced from and rotatable with the bottom of the container, a band loosely mounted on the container and constituting a closure therefor, said band having spiral slots, projections on the container and within the slots, a projection 110

upon the band, and fixed means in the path of said projection for holding the band against rotation during a portion of the rotation of the container, thereby to release 5 the contents of the container.

6. The combination with a spiral guide stem and a support therefor, of a container mounted to gravitate and rotate upon the stem, a broadcasting disk spaced from but 10 rotatable with the bottom of the container, means for holding the container against rotation, time controlled means for releasing the container, means for imparting an initial impulse to the rotation of the container 15 when released, a closure for the container, and means for retarding the movement of the closure during the actuation of the container, thereby to release the contents of the container.

7. The combination with a spiral guide 20 strip and a support therefor, of a disk mounted to gravitate and rotate upon the stem, a container having an outlet at the bottom, cooperating means upon the disk and container for rotating the container 25 with the disk during the downward movement of the disk and container but permitting rotation of the disk independently of the container during the upward movement of said container, a closure for the container, 30 and means for shifting the closure relative to the container during the actuation of the container.

In testimony that I claim the foregoing as my own, I have hereto affixed my signature. 35

ROBERT CARL OLSON.
